UNITED STATES PATENT OFFICE.

FRANK KUHN AND JAY A. HAND, OF DETROIT, MICHIGAN, ASSIGNORS TO AMERICAN ELECTRICAL HEATER COMPANY, OF DETROIT, MICHIGAN, A CORPORATION OF MICHIGAN.

ELECTRIC IMMERSION-HEATER.

1,288,044.

Specification of Letters Patent.

Patented Dec. 17, 1918.

Application filed February 21, 1918. Serial No. 218,401.

To all whom it may concern:

Be it known that we, FRANK KUHN and JAY A. HAND, both citizens of the United States of America, both residing at Detroit, 5 in the county of Wayne and State of Michigan, have invented certain new and useful Improvements in Electric Immersion-Heaters, of which the following is a specification, reference being had therein to the accompanying drawings.

The invention relates to electric heaters designed for use in the heating of liquids by immersion thereinto, and the invention comprises the novel construction as herein- 15 after set forth.

In the drawings:

Figure 1 is a perspective view of the heater;

Fig. 2 is a central longitudinal section 20 therethrough;

Fig. 3 is a cross-section on line 3—3 Fig. 2;

Fig. 4 is an elevation of a portion of the heating unit showing the manner of winding the same; and

Fig. 5 is a perspective view illustrating the manner of assembly.

For many uses it is desirable to have an immersion heater which is of comparatively 30 high electrical resistance and is also very compact so that it may be inserted into a small vessel. With our improved construction the heating element is placed in a cylindrical casing of small dimensions, which 35 in turn is connected with a similar tubular shank for the terminal conductors having a plug socket at its outer end. The heating unit is formed of a series of flat thin insulator cores, preferably of mica, on which is wound a continuous resistor, and the several 40 sections are insulated from each other by interposed strips of mica or other insulator.

In detail, and as shown in Figs. 4 and 5, A A', etc., are the mica core strips, which 45 are formed with apertures B B' for the passage of clamping screws and around which is spirally wound a continuous resistor C. The resistor passes across from one strip to the adjacent one alternately at opposite 50 ends so as to permit of assembly in zigzag form, as shown in Fig. 5. Mica strips D of greater width are then inserted between the adjacent resistor-wound strips so as to separate and insulate the same, and correspond- 55 ing insulating strips are placed outside the

outer resistor-wound sections, all being held in proper relative position by the aligned apertures, B therein. E are heat-absorbing and distributing clamping plates arranged upon opposite sides of the series of sections 60 and secured to each other by the clamping screws F. These plates and screws hold the series from displacement and also place sufficient pressure thereon to insure good heat conducting contact. Any desired resistance 65 may be imparted to the resistor by increasing or diminishing the number of wound sections, and on account of the good heat conduction the inner sections will not rise in temperature above the safe limit. 70

The heating unit formed as described is inserted in a tubular outer casing G, closed at one end and at its opposite end engageable with a shank tube H through which the terminal ends of the resistor pass. These 75 terminal portions are insulated by surrounding insulator tubes I and at their outer ends are connected with enlarged terminal contacts J. These terminal contacts are secured to an insulator block K which is housed in 80 a metallic casing L, which casing telescopically engages the shank tube H. Thus in assembling, the housing L may be drawn downward on the shank to permit of attaching the terminals to the contacts J, after 85 which the housing is slipped up to inclose the insulator block K and terminals and to form a socket for receiving the connector plug. The entire casing may be rendered 90 liquid tight by soldering or otherwise sealing the joints between the shank H and the casings G and L.

The construction as described may be used by inserting the casing into the liquid to be heated and engaging a plug, such as M, with 95 the socket in the casing L. The heat generated in the resistor passes rapidly outward through the heat-absorbing and distributing members E, which, being in heat conducting relation to the outer casing, will quickly 100 transfer the heat to the liquid.

What we claim as our invention is:

1. An electric immersion heater, comprising a heating unit having a series of superposed flat sections wound with a continuous 105 resistor with interposed flat insulation, heat-absorbing and distributing members clamped upon opposite sides of the series, having flat faces for engaging the same and forming in connection therewith complementary por- 110

tions of a circular cross-section, and a tubular casing in which said unit is inserted closed at its lower end and having terminal connections at its upper end.

- 5 2. An electric immersion heater, comprising a flat elongated heating unit, heat-absorbing and distributing members on opposite sides of said heating unit and segmental in cross-section to form complementary portions of a circular cross-section, a tubular housing closed at its lower end and receiving said heating unit, a tubular shank of smaller diameter through which the terminal ends of the resistor pass, a terminal 10 socket having an end portion for fitting said tubular shank, and means for sealing the joints between said tubular shank, the tubular casing and said terminal socket.
- 15 3. An electric immersion heater, comprising

ing a flat elongated heating unit, segmental 20 heat absorbing and distributing members clamped upon opposite sides of said heating unit, a tubular housing closed at its lower end and receiving said heating unit, a tubular shank of smaller diameter through 25 which the terminal ends of the resistor pass, an insulator block at the outer end of said tubular shank, terminal contacts thereon adapted for engagement with the terminal ends of the resistor, and a housing telescopically 30 engaging said tubular shank, and inclosing said insulator block and terminal contacts.

In testimony whereof we affix our signatures.

FRANK KUHN.
JAY A. HAND.
